PALLET OR SIMILAR ARTICLE

John Earl McCorkle and Lewis Byron Hasking, Littleton, and Howard Arthur Seeber, Larkspur, Colo., assignors to Johns-Manville Corporation, Denver, Colo.

Continuation-in-part of abandoned design application Ser. No. 460,003, Apr. 11, 1974. This application May 8, 1975, Ser. No. 575,900

Term of patent 14 years

Int. Cl. D9—99

U.S. Cl. D12—53

FIG. 1 is a top perspective view of a pallet or similar article showing our new design;

FIG. 2 is a bottom perspective view thereof.

FIG. 3 is a fragmentary sectional view taken on the line 3—3 of FIG. 1 and illustrating in detail the central portion thereof.

The side and end opposite to those shown in FIG. 2 are mirror images of the side and ends shown therein.

This application is continuation-in-part of design application Ser. No. 460,003, filed Apr. 11, 1974, and now abandoned.

We claim:

The ornamental design for a pallet or similar article, as shown and described.
